(57) **CLAIM**

The ornamental design for a chair, as shown and described.

DESCRIPTION

FIG. 1 is a front perspective view of the chair.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof; and,

FIG. 8 is mirror image of the right side elevation view of the chair.

The broken lines shown in the drawings illustrate portions of the chair that form no part of the claimed design.

1 Claim, 4 Drawing Sheets

FIG. 2

FIG. 1

FIG. 4

FIG. 3

FIG. 5

FIG. 6

FIG. 7

FIG. 8
